(57) **CLAIM**

The ornamental design for an elevator indicator, as shown and described.

DESCRIPTION

FIG. 1 is a front and top perspective view of an elevator indicator showing a first embodiment of our new design; FIG. 2 is a front view thereof;

FIG. 3 is a top view thereof;

FIG. 4 is a bottom view thereof;

FIG. 5 is a left side view thereof;

FIG. 6 is a right side view thereof;

FIG. 7 is a front and top perspective view of an elevator indicator showing a second embodiment of our new design; FIG. 8 is a front view thereof;

FIG. 9 is a top view thereof;

FIG. 10 is a bottom view thereof;

FIG. 11 is a left side view thereof; and,

FIG. 12 is a right side view thereof.

The broken lines illustrate portions of the elevator indicator and form no part of the claimed design.

The solid black surface shading represents the color black.

1 Claim, 10 Drawing Sheets
